Garrettson Smith & Henry Brown, of Philadelphia, Pa:
Assignors to

Leibrandt, McDowell & Company, of the same place.
Letters Patent No 960 - Dated Oct. 20th 1857.

~~~~~  
The schedule referred to in these Letters Patent is making part of the same.  
~~~~~

To all whom it may concern,

Be it known, that we Garrettson Smith and
Henry Brown, both of the City of Philadelphia and State of Pennsylvania
have invented or produced a new and original design for a cook-
ing stone, termed the "Governor" and we do hereby declare that the following
is a full and exact description of the same reference being had to the ac-
companying drawing, and to the letters of reference marked thereon.

Fig: 1. is a side view of the "Governor" cooking stone.

Fig: 2. a top view of the same.

Fig. 3. a front view.

Fig. 4. a back view

Fig. 5. a sectional view (full size) of the moulding round the top plate.

Fig. 6. a sectional view of the moulding round the hearth.

Similar letters refer to similar parts throughout the several views.

A. is the top plate of the stove, the form of the moulding on its edge being shown in Fig. 5. B. represents one of the side plates on which are hung the oven door a, the door b, for the opening which communicates with the firebrick lining of the fire place, and the door d, for the lower portion of the oven. C. is the hearth plate the moulding on the edge of which is seen in section at Fig. 6. D. is the front plate of the stove having upper doors e. e. and lower doors f. f. in front of the firebars, and a door g at the bottom which covers an opening communicating with the flue - E. is the back plate, & G. the bottom plate of the stove.

We claim the combination and arrangement of ornamental figures and forms represented, forming together an ornamental design for a cooking stove.
